Primary Examiner — Jack Reickel*Assistant Examiner* — Michael A Kervin(74) *Attorney, Agent, or Firm* — Kofi A. Schulterbrandt(57) **CLAIM**

The ornamental design for a wrench rack, as shown and described.

DESCRIPTION

FIG. 1 is a front perspective view of a wrench rack;

FIG. 2 is a front elevation view thereof;

FIG. 3 is a rear elevation view thereof;

FIG. 4 is a right side elevation view thereof;

FIG. 5 is a left side elevation view thereof;

FIG. 6 is top plan view thereof; and,

FIG. 7 is a bottom plan view thereof.

The broken line showing of a wrench rack is for the purpose of illustrating portions of the article and forms no part of the claimed design.

1 Claim, 7 Drawing Sheets
